UNITED STATES PATENT OFFICE

HERMAN A. BROCKHAUS, OF WOODWARD, OKLAHOMA.

GREASE-CUP.

1,088,804.

Specification of Letters Patent. Patented Mar. 3, 1914.

Application filed August 23, 1912. Serial No. 717,556.

To all whom it may concern:

Be it known that I, HERMAN A. BROCKHAUS, a citizen of the United States, residing at Woodward, in the county of Woodward and State of Oklahoma, have invented new and useful Improvements in Grease-Cups, of which the following is a specification.

This invention relates to lubricators for vehicle axles and has for its objects to provide a device of this character which may be readily connected with the hub of the wheel and arranged in open communication with the axle; one which will be positive in action, simple, strong and durable, and one which will insure the maximum discharge of the lubricant from the container.

In the drawing forming a portion of this application, and in which like characters of reference indicate similar parts in the several views:—Figure 1 is a side view of a vehicle wheel showing the application of the lubricator thereto, parts being shown in section. Fig. 2 is a similar view showing the follower 25 in a lowered position. Fig. 3 is a section through a portion of the cup and through the feed tube showing the manner of connecting the latter with the former.

The vehicle wheel 1 herein illustrated is of the usual well known construction, the hub 2 thereof having a radial threaded passage 3 therein which opens directly into the box 4 so that the lubricant may be fed directly to the axle 5.

The lubricator 6 which is designed to permit the lubricant to be readily fed to the axle 5 comprises, a feed tube 7 radially disposed upon the hub 2 and extended into the passage 3 and correspondingly threaded to accommodate itself therein in such manner as will effectually serve to retain the device properly mounted upon the wheel, as is evident. The outer end of the tube 7 projects considerably beyond the peripheral surface 45 of the hub, where it is extended through a passage 8 in the substantially spherical bottom of the cup or lubricant container 9, being upset at 10 against the inner wall of said bottom. An integral nut portion 11 of the tube bears against the external walls of said bottom whereby to coöperate with said

upset portion 10 in securely connecting the cup with the tube, as is evident. From said spherical bottom of the cup the cylindrical side walls 12 extend, being exteriorly threaded to receive the correspondingly threaded internal side walls 13 of a combined follower and cap 14. The said follower 14 has its head 15 provided with a threaded passage 16 in which is adjustably mounted a follower 60 screw 17 to which is secured a follower head 18 of substantially semi-spherical configuration whereby to conform exactly with the curved internal walls of the cup bottom on one adjustment of the screw. It is also 65 stated that the head 18 has a transverse diameter equal to the internal diameter of the cup whereby the former can move freely in the latter. The head 18 is provided with a flat surface 19 which may be brought to bear 70 against the head 15 of the cap 14 on another adjusted position of the screw 17, as shown in Fig. 1. In this manner it is seen that adjustment of the head 18 to the last described position maximizes the lubricant containing 75 volume of the cap 14, while adjustment of the head 18 to the first described position insures the maximum discharge of the lubricant as will be understood through the fact that the convexity of said head is adapted to 80 lie wholly in contact with the concavity of the bottom of the lubricant cup.

The nut portion 11 furnishes means whereby the tube can be quickly connected in the passage 3 of the hub 2, while the knurled 85 surface of the cap 14 furnishes means whereby the cap can be manually adjusted to force the lubricant into the discharge tube 7. A manipulating wheel 20 of the feed screw 17 may be turned by the hand to feed the follower head 18 toward the curved bottom of the cup, as the occasion may demand.

I claim:—

A lubricator comprising a cup having a bottom of concavo-convex form and cylindrical side walls extending from the bottom and exteriorly threaded throughout their length, a discharge tube leading from the bottom, a cap provided with an internally threaded depending flange adjustably engaging the threaded walls and provided with a head overlying the upper end of the

cup and serving initially as a follower to compress the lubricant and force the same into the cup for discharge through the tube, and a follower adjustably mounted in the 5 cap and provided with a head having an upper smooth surface normally engaging with the inner side of the head of the cap and a convex bottom conforming to the con-

cavity of the bottom of the cup and adapted to be adjusted with relation to said bottom. 10

In testimony whereof I affix my signature in presence of two witnesses.

HERMAN A. BROCKHAUS.
